MANIFOLDING ATTACHMENT

John Q. Sherman and Albert W. Metzner, Dayton,
Ohio; said Metzner assignor to said Sherman

Application December 23, 1933, Serial No. 703,694

16 Claims. (Cl. 197—126)

This invention relates to writing machines, and particularly to manifolding means for typewriters wherein multiple superposed strips of record material and interleaved portions of transfer material are simultaneously fed about a platen roll, and especially to means for compensating for the differential travel of the different strips due to their different radial distances from the axis of rotation whereby their effective travel will be equalized and accurate registry of printed forms thereon maintained.

In traveling about a platen roll each succeeding stratum of record material being a greater distance from the axis of the roll will have a greater peripheral path of travel than that closely adjacent to the roll. When but a few sheets of short length are used, this differential is but slight and negligible. However the error is cumulative and in the use of continuous strips of series connected stationery of indefinite length, superposed forms are gradually offset until such deviation becomes quite serious. This difficulty also increases with increase in the number of superposed sheets or strips, the displacement of which out of registry occurs more rapidly.

It is highly desirable that accurate registry be maintained at the writing line regardless of the number of copies and the length of the strips.

In the present construction, the differential travel of the superposed strips is compensated and corrected by passing the strip assembly successively about different rolls or guides in such relation that the innermost and hence the slowest traveling strip when passing about one roll becomes the outermost and fastest traveling strip when passing about the second roll. The relative speeds of the different strips while passing about the different rolls vary with their distances from the centers of rotation. Their decrease of speed about one roll offsets their increase of speed about the other roll so that the relative speeds are equalized and the several strips are presented in registry at the writing position. This may be accomplished by various arrangements of rolls, several of which are illustrated in the drawings.

Additional to the travel compensating means the present invention embodies improved retracting means for the transfer material by which relatively short carbon sheets are advanced in unison with the record strips, and subsequently retracted independently of the record strips into registry with succeeding portions thereof preparatory to the next writing operation.

The object of the invention is to improve the construction as well as the means and mode of

operation of strip feeding and carbon shifting apparatus whereby they will not only be simplified but will be more efficient in use, uniform in operation, automatic in action, easily controlled and unlikely to get out of repair.

An important object of the invention is to provide means for equalizing the travel of a relatively large number of superposed record strips whereby corresponding portions will accurately register at the writing position.

A further object of the invention is to provide means for positively feeding such superposed strips of record material past writing position.

A further object of the invention is the provision of improved positive feeding mechanism automatically engaging and disengaging the material to progressively advance the strips in predetermined relation.

A further object of the invention is to provide improved control means for the record and transfer material feeding means.

A further object of the invention is to provide improved transfer material retracting mechanism, and actuating means therefor.

A further object of the invention is to provide an improved mounting and guide for the transfer retracting means.

A further object of the invention is to provide manifolding material feeding means possessing the hereinafter mentioned desirable characteristics and meritorious features.

With the above primary and other incidental objects in view, as will more fully appear in the specification, the invention consists of the features of construction, the parts and combinations thereof, and the mode of operation, or their equivalents, as hereinafter described and set forth in the claims.

view, showing the carbon carrier retracting means. Figs. 10 and 11 are detail views, illustrating the pin wheel unit for positively advancing superposed record strips. Fig. 12 is a perspective view, illustrating the use of fan-fold material. Figs. 12A and 12B are detail views. Fig. 13 is a detail perspective view of a transfer material holder for engagement with the retracting device. Figs. 14 and 15 are respectively a side elevation and a perspective view observed from the rear of a modification wherein in lieu of extending upwardly and rearwardly from the writing machine, as illustrated in Fig. 1, the apparatus forming the subject matter hereof is disposed vertically at the rear of the typewriter. Fig. 16 is a perspective view observed from the rear of a further modification embodying an endless belt feeding means for the superposed strips in lieu of the pin wheel unit associated with the respective rollers of the preceding construction. Fig. 17 is a side elevation thereof. Figs. 18 and 19 are perspective views observed from the front and rear respectively, illustrating further modifications. Figs. 20 and 21 are detail diagrammatic views. Fig. 22 is a fragmentary perspective view, illustrating strip engaging grippers mounted upon the transfer material carrier and operatively connected with the retracting means.

Like parts are indicated by similar characters 30 of reference throughout the several views.

The present manifolding apparatus is applicable to any standard typewriter, biller, or other writing machine 1 and is shown in the drawings supported for to and fro travel upon the reciprocating platen carriage of the writing machine. Obviously, if so desired, this manifolding apparatus may be supported independently of the writing machine but operatively connected therewith for unison travel movement.

40 The manifolding apparatus includes a main frame having parallel side bars 2-2 which are preferably, though not necessarily, of angle formation, the opposite ends of which are transversely interconnected by rods 3-3 into a rigid rectangular frame. The frame bars 2-2 are embossed or perforated if desired, at regularly spaced intervals, as indicated at 4, to provide series of rack teeth for engagement of a gear pinion upon a traveling carrier for transfer material. A mounting plate for a gripper mechanism is fixedly secured adjacent to the lower ends of the side bars 2 and the structure may be rigidly braced by suitable trussing, not shown in the drawings. The frame is supported in an 50 upwardly and rearwardly inclined position by notched brackets 7 engageable over spaced studs 8 projecting from the traveling platen carriage of the writing machine with which the bracket is held in engagement by an adjustable hook-shaped detent 9. At the top of the frame there is journaled a compensating roller 10 mounted in suitable brackets 10a. The compensating roll is provided with successions of spaced feeding pins 11 engageable in marginally punched holes 12 in superposed strips 13 of record material. The record material strips are progressively fed from a supply packet 14 at the rear of the writing machine upwardly at the rear of the frame and thence over the compensating roll 10 and in 60 a downwardly direction, in alternating relation with interleaved sheets of transfer material 15 at the front of the frame, to the platen roll 16 of the writing machine. The platen roll 16 operates in the usual manner of conventional writing machines to advance the record material

by frictional engagement of pressure rollers cooperating with the platen roll. The record strips 13 pass in reverse directions about the compensating roll 10 and the platen roll 16. These rolls are of the same or different diameters and the 5 strips travel thereabout in reverse order, the innermost strip when passing about the compensating roll becomes the outer strip when passing about the platen roll. Thus any increased speed of lineal travel and relative gain of the 10 outermost strips in passing the compensating roll due to their greater distance from the axis and consequent greater peripheral travel, is offset or compensated for by their less speed when passing, as the innermost strips about the platen 15 roll, in unison with which the compensating roll rotates. The feeding pins 11 serve to maintain accurate registry of printed forms on the respective strips, and are preferably, though not necessarily mounted in the compensating roll for reciprocatory motion in radial directions into and out of engagement with the punched margins of the record strips 13. To this end the feeding pins 11 are preferably slidably mounted in radial 20 guide grooves 17 in the compensating roll. The 25 inner ends of the pins are notched for sliding engagement upon a stationary flanged cam 18 interiorly of the roll 10 about which the pins travel in unison with the rotation of the compensating roll. As the pins approach the eccentric or more distant portion of the cam 18, they 30 are projected beyond the periphery of the roll 10 into engagement with the punched margins of the strips, and as they continue their travel therebeyond onto the concentric portion of the 35 cam, the pins are automatically withdrawn from the record material and again retracted within the roll. A limited number of feeding pins are always in engagement with the strips, engagement and withdrawal thereof being progressive. 40 Thus the registry of printed forms upon the several strips and the alinement of the strips with each other is automatically maintained at this point. Slidably mounted upon the side bars 45 2-2 of the frame is a vertically movable carrier 20 for the interleaved transfer sheets 15. The carrier 20 is provided with rearwardly extending ears or brackets 21 in which is journaled a transverse shaft 22 carrying at its ends gear pinions 23. These pinions intermesh with the rack teeth 4 upon the frame bars 2 to insure uniform travel of the carbon carrier 20 and maintenance of its parallel movement throughout its range of travel. The transfer material being interposed between the record strips and advanced in unison therewith by the platen roll 16 and coacting pressure rollers draws the carrier 20 downwardly against the retarding influence of a brake mechanism 24 mounted upon the transverse shaft 22 at the rear of the carrier and yieldingly resisting the rotation of the shaft and gear pinions 23 which have intermeshing engagement with the rack teeth 4. This brake device consists of a sleeve 25 carried by the shaft 22 upon which are mounted a series of discs 26 certain of which are rotative with 50 the sleeve and shaft, while alternating discs are non-rotatively engaged with the carrier 20. They are pressed into frictional engagement with each other by a tension spring 27 which abuts at its opposite end upon a pair of lock units or stop 55 collars 28 screw threaded upon the sleeve. The carbon carrier 20 is provided with forwardly extending hook shaped fingers 29 from which are suspended intermediate the record strips 13 the plurality of sheets of transfer ma- 75

70

terial 15 each mounted in a separate hanger. The transfer material hangers comprise strips or bars 31 the length of which is greater than the width of the record strips and transfer material, and provided at their ends with eyes or holes 32 engageable over the hook shaped fingers 29. Pivoted to each hanger bar 31 is a channel shaped retainer 33 which when turned to parallelism with the bar 31 overlaps at opposite sides of the bar the terminal portion of the transfer sheet 15 which has been folded over the hanger bar. Registering embossed ribs 34 in the bar and retainer serve to yieldingly hold the retainer in clamping relation with the engaged portion of the transfer sheet.

In the event that fan fold record material 13a is employed, the hook shaped fingers 29 are arranged in pairs at opposite sides of the path of travel of the record material and the hangers 20 have a pair of spaced holes at one end agreeing with the spacing of such fingers for engagement therewith as shown in Fig. 13 with the free ends of the hangers extending intermediate the respective folds of the fanfold record material 13a. Thus instead of the transfer material hangers being supported at each end beyond the path of travel of the record material, they are each supported wholly at one end beyond one margin only of the record material, the succeeding hangers 30 being thus mounted alternately at opposite sides thereof.

In addition to the suspension fingers 29 the transfer material carrier 20 is provided with spaced guide pins 35 which define the path of travel of the record material therebetween and prevent lateral displacement of the record strips relative to the transfer material.

To facilitate the retraction of the carrier 20 and interconnected transfer material preparatory to each succeeding writing operation, the carrier is provided with laterally extending handles or finger grips 36 to be grasped by the operator for retracting the carrier upwardly. In lieu of the handles 36 for retraction of the transfer material carrier, which necessitate a lifting motion, one of the frame bars 2 is preferably provided with a slotted guide way 37 in which is mounted a reciprocating slide 38 having a finger engaging extension 39 and which is connected with the carrier 20 by a flexible strap or cable 40 passing over suitably located guide sheaves 41 supported upon the frame.

In the event that the record strips 13 are positively engaged with the transfer material carrier 20 during the unison advance movement of the strips and carriers, by means of eccentric gripper rolls 42 against the influence of an actuating spring 43 and retractable against the influence of an actuating spring 43 to release the strips by oscillation of an arm 44, as described in Letters Patent No. 2,063,959, issued December 15, 1936, upon a co-pending application, and illustrated herein in Fig. 22 the retracting cable or strap 40 may be connected to a transverse rod 45 connecting arms 44 at the opposite sides of the carrier whereby the initial downward pulling influence upon the finger slide 38 will oscillate the arms 44 to release the strips from the eccentric gripper rollers 42 preparatory to retraction of the carrier and transfer material by further movement of the slide 38. The transfer material carrier is actuated downwardly during the advance movement of the record strips by the pulling influence upon the interleaved transfer sheets 15 of the platen roll by which the record strips are

advanced. The downward motion of the transfer material carrier is transmitted to the compensating roller by a cord or cable 46 attached at one end to the carrier 20, the opposite end of which is connected to and wound upon a grooved pulley 47 mounted concentric with the compensating roller at one end thereof. The grooved pulley 47 encloses a spiral retracting spring 48, one end of which is fixed while the other end is attached to the pulley. The grooved cable pulley 46 and the compensating roller 10 are interconnected for unison rotation in one direction by a pawl 49 on one member engageable with a ratchet wheel 50 on the other member. As the transfer material carrier descends during the writing operation, the pull upon the cable 46 unwinds it from the grooved pulley 47 causing the pulley to rotate and carry with it the compensating roller during such rotary movement. This rotation of the pulley is contrary to the influence of the spring 48 and serves to wind or tension such spring. Upon retractive movement of the transfer material carrier, the grooved pulley 47 is rotated in reverse direction independently of the compensating roller by the retractive influence of the coiled spring to rewind the cable 46. During such retractive movement if desired the compensating roller may be held against reverse rotation by a detent pawl and ratchet device preferably located at the end of the roll 10 opposite the pulley 47. At the lower end of the main frame is an apron 51 beneath which the record strips 13 and interleaved transfer sheets 15 pass to the platen roll 16 of the writing machine. The guide apron 51 is elevated somewhat above an underlying transverse plate 52 connecting the side bars 2-2 of the frame beneath the record and transfer material and on which are mounted grippers 53 pivoted to ears 54 projecting from the frame plate 52. The grippers 53 are spring actuated into engagement with the margins of the record material beyond the margins of the transfer material by retracting springs 55 connected to rearwardly extending mounting fingers 56. They are elevated out of engagement with the record strips against the tension of the springs by finger levers 57 also pivoted to suitable ears on the frame plate 52, and carrying rollers 58 engaging the spring actuated grippers. The relation of the finger trip levers and gripper is best shown in Figs. 3 and 4. The grippers at opposite sides of the frame are interconnected for unison operation.

Spring guide fingers 59 project downward from the apron 51 in overhanging relation with the record material to confine such material and prevent bulging distortion.

There are several ways in which the apparatus may be manipulated to facilitate the periodic retraction of the transfer material. The transfer material carrier having been progressively drawn down the frame and the transfer material correspondingly advanced in unison with the travel of the record strips 13 under feeding action of the writing machine platen roll operating in its usual manner, until the inscription of a given length of the strips of record material or a set of printed forms thereon has been completed, the portions of the transfer material sheets 15 extending about the platen roll will be found to be tightly held between the superposed record strips and resistant to retractive movement. In one mode of operation, employing transfer sheets 15 of less width than the record strips, whereby the strips marginally project beyond the trans-

fer material, at the limit of the advance or feeding movement of the material, the finger lever 57 is tripped to permit the grippers 53 to descend into clamping engagement with the margins of the record strips 13 thus holding the record strips immovably in their advanced position, independently of the transfer material. Upon relief of the pressure of the frictional rolls cooperating with the platen, by operation of the usual pressure control lever 60 on the writing machine, the transfer material is released together with the portions of the strips 13 about the platen roll, and the transfer material may be retracted by retraction of the carrier 20 upwardly upon the frame, thereby withdrawing the transfer sheets from between the inscribed portions of the strips into registry with the next succeeding portions or forms to be inscribed, and the previously inscribed portions are detached on transverse weakening lines provided for such purpose. During such relative adjustment the record strips have been held in registry by the clamping action of the grippers 53. Upon disengagement of the grippers by reverse movement of the finger trip lever 57 and reengagement of the pressure rolls the material is ready for repetition of the writing operation.

As an alternative mode of manipulation, employing transfer and record material of either equal width or different widths, the record strips and transfer sheets are arranged with their free ends in overlapping relation by extending the terminal portions of the record strips beyond the ends of the transfer material. Such terminal portions of the strips are customarily occupied by headings upon the printed forms, or other areas which are not to be inscribed, and hence underlying transfer material is unnecessary. The record material and transfer material are fed through the writing machine in unison in the usual manner by the feeding action of the platen roll and associated friction rollers. When the inscription of a given length of record material or terminal form thereon has been completed the platen roll of the writing machine is reversely operated to retract in unison the record strips and interleaved transfer material until the transfer material has been retracted beyond the point of feeding engagement of the platen roll and associated frictional pressure rollers, and the overlapping ends of the record strips only, beyond the transfer material, are engaged by the writing machine feeding means. The transfer material carrier is retracted a like distance in unison with the retraction of the record strips and is then given a slightly further independent retractive movement, equivalent to the overlap or extension of the ends of the record strips beyond the ends of the transfer sheets. The carrier and attached transfer sheets are held in such retracted position by the operator maintaining the operator slide 38 in its depressed position while the writing machine feeding means is operated to advance the record strips 13 independently of the retracted transfer material until the previously inscribed portion or set of forms are advanced beyond the platen roll and in position for detachment and the advance ends of the succeeding portion or set of forms to be inscribed are engaged with the writing machine feeding means. The inscribed portions of the strips are then detached and the cycle of operation beginning with the inscription of the succeeding portion or set of forms during which the transfer sheets and carrier again ad-

vance in unison with the record strips, is then repeated.

By either method of manipulation, the record strips 13 are always held securely in place during the shifting operation, while the transfer sheets 5 are released for independent shifting adjustment into interleaved relation with the succeeding portion to be inscribed, or set of printed forms as the case may be. Accurate registry and alinement of the superposed strips of forms is insured by 10 the use of the compensating roller 10 acting cooperatively with the platen roll of the writing machine to equalize the travel of multiple strips regardless of their distances from the center of rotation and consequent variation of extent of 15 peripheral travel, and the periodical release at the friction platen roll to correct any discrepancies in registry appearing at that point.

While the form of embodiment heretofore described and as illustrated in Figs. 1 to 10 inclusive is preferable and that heretofore adopted for commercial use, the fundamental features of the invention may be embodied in other forms of apparatus, some of which are herein illustrated.

In Figs. 14 and 15 there is shown a modification 25 wherein the main frame comprising the side bars 2-2 interconnected by the transverse tie rods 3 is vertically arranged at the rear of the writing machine, and the traveling transfer material carrier 20 ascends the frame during the feeding operation and is retracted downwardly, or conversely of the travel movements as heretofore described. In this construction the compensating roller 10 is mounted at the top of the main frame and is actuated in unison with the rotation of 35 the writing machine platen roll 16 by a train of gears 61 but rotates in the opposite direction. The superposed record strips 13 pass to the apparatus beneath a guide rod 62 at the bottom of the frame, and pass upwardly over the traveling carrier 20 and beneath the transfer sheets before reaching the compensating roller 10. The transfer material for use in this form of embodiment must necessarily be longer than that used in the primary construction first described. Such transfer material must be of sufficient length to extend from the carrier 20 when retracted over the compensating roller and thence downwardly between the strips 13 to the platen roller 16 of the writing machine. The frame is detachably supported upon arms 63 extending upwardly and rearwardly from the writing machine platen carriage, and in which the idler gears 61 of the gear train are mounted. Mounting brackets 7 carried by the frame engage over spaced studs 8 on the arms 63 55 with which they are held by the latch hook 9, in the same manner as before described.

In Figs. 16 and 17 there is illustrated a further variation wherein in lieu of the radially disposed aligning and feeding pins 11 upon the compensating roll 10, the compensating roll is devoid of strip engaging means and endless traveling belts 64 disposed in the rear of the main frame are provided with strip engaging studs 65, which by engagement in the punched holes of the record strips, serve to progressively feed the strips upwardly and over the compensating roller. The belts 64 pass over sprockets 66 of suitable size at each end and are driven in unison with the rotation of the platen roll, preferably, though not necessarily by interconnection of the lowermost sprocket with the platen roll. The platen roll is provided with a gear 67 intermeshing with a second gear 68 with which is connected a driving sprocket 69 connected by a drive chain 70 with a 75

driven sprocket 71 upon the same shaft with the lowermost sprockets 66 by which the conveyor belts 64 are carried. Like the primary construction the compensating guide may be the roller 10 or may be a stationary form of arcuate guide, which in either event may be of greater or less radius than the platen roll 16 and in this form of device it is actuated solely by the pull of the strips 13 passing thereover. At the back of the 5 apparatus there is provided a pair of relatively spaced slotted guide plates 72 between which the record strips pass upwardly to the compensating roll. The strip engaging pins 65 project through and travel longitudinally of the longitudinal slots 10 in the spaced guide plates 72, and have feeding engagement with the record strips therebetween. Such strips may be marginally punched as illustrated in connection with the primary construction, or they may be merely provided with feeding 15 holes 13 at widely spaced intervals for engagement of the studs 65. To facilitate introduction of the strips the outermost plate 72 may be hinged at 74 at its upper end.

The traveling transfer material carrier 20 may 20 be mounted for vertical travel on the frame in the manner before described and as illustrated in Figs. 1, 2, 4 and 9. In lieu thereof the carrier may be omitted and continuous strips of "one time" carbon may be interleaved between the record 25 strips. Likewise, when "one time" carbon is used and the necessity for carbon shifting means is obviated, the compensating guide 10 may be mounted directly upon the platen carriage of the writing machine in juxtaposition to the platen 30 roll 16 as is illustrated in Figs. 18 and 19. In such construction the compensating roll 10 is mounted in supporting brackets 75 secured to the platen carriage and carries a sprocket wheel with which engages the drive chain 70 actuated 35 from the platen roll by a gear pinion 67, meshing with a second gear 68 to which is attached a driving sprocket 69, in a manner quite like that shown in Figs. 16 and 17. The compensating roller 10 is provided with reciprocating disappearing feeding pins 11 and functions to correct 40 the differential travel of the strips due to their varying distances about the axis of rotation of the platen roll. To achieve such correction within practical limits it is quite desirable that the strips engage both rolls 10 and 16 through 45 substantially equal angular extent, and illustrated diagrammatically in Fig. 20.

While for economy of production and to enable 50 the use of the same stock material for the platen roller 16 and the compensating roll 10, these rolls have been shown and heretofore described as of the same size, this is not an essential factor and the compensating roller 10 may be either larger or smaller than the platen roll 16, without changing 55 the result. In fact the compensating device need not necessarily be a roller but may be merely a stationary guide about which the strips are drawn, as is shown at 75 in Fig. 21. The controlling factor in any instance is the angular extent 60 to which the strips conform to the platen roller and to the compensating device. Referring to the diagrammatic views Figs. 20 and 21, the angle $a-x-b$ which defines the limits of the arcuate travel of the strips about the platen roller 65 must approximate the angle $c-x-d$ which defines the limits of arcuate travel of the strips about the compensating device, whether it be the roller 10 or the guide 75.

While in Fig. 12 there is shown means for 70 mounting the transfer sheet hangers at one side

of the record material for cooperation with fan fold material, it may sometimes happen that the sheets of transfer material will not exactly align with the record material. To correct this condition the transfer sheet hangers are mounted 5 upon a swinging arm 76, as illustrated in Fig. 12A, which is pivoted to the traveling carrier 20 coincident with the mounting hook or curved finger 29, beyond which one or more studs 77 are carried by the arm 76. The transfer sheet 10 hanger is provided with a series of holes, as is illustrated in Fig. 12B, one of which receives the hook or curved finger 29 as before described and the other holes are located to receive the studs 77. The arm 76 is swingingly adjustable about 15 the hook or curved finger 29 within the range defined by an arcuate slot 78 in the carrier 20 through which a clamp screw 79 engages with the arm 76 from the rear of the carrier, to secure 20 the arm 76 in adjusted position.

In maintenance of registry of printed forms upon superposed strips of record material while being fed through a writing machine there are ordinarily three factors of error to be overcome. First: there is always present certain variations 25 of the spacing of succeeding printed forms due to inequalities in the paper manufacture, and in the printing and punching of the strips, also variations of moisture content and consequent expansion and contraction of the strips which 30 may vary from day to day in the same material, and inequalities due to the association of strips of different material or of the same material having different physical characteristics. Second: when superposed strips are advanced 35 through an arcuate path of travel whether it be about a platen roller of a writing machine or turned about a guide rod or other means by which its direction of travel is changed, there will occur a differential of travel by which one 40 or more strips will gain upon another due to their different radial distances from the center of curvature, or it may be said that one or more strips lag behind another. Third: certain types of 45 feeding devices are inherently ununiform in their action and also with the use of friction feed devices a small amount of slippage may occur, especially under unfavorable operating or atmospheric conditions and with certain types of material. The present construction is designed to 50 overcome the various difficulties and insure uniform feeding motion of the strips and accurate registration of the printed forms. The initial 55 registry and alignment is effectively accomplished by the pin type feeding devices, whether they be the pin wheel units or traveling belt conveyors having strip engaging pins, both of which have been illustrated. The travel differential of the strips due to their passage about the platen roller of the writing machine at different distances from its axis, and hence through circumferential paths of different extent is anticipated and compensated for in advance by passing the strips through a converse arcuate path whereby 60 the differential travel of the strips is effected in reverse order during their advance toward the platen roll, and the differential resulting from their passage about the platen roll merely restores the strips to their original relation in which they were registered and aligned by the 65 pin type feeding devices. If due to defective frictional pressure rollers, unusual operating conditions or the particular character of the material, slippage or other feeding error shall occur during the travel of the strips about the 70 75

platen roller, such error automatically corrects itself upon the release of the strips from the friction roller pressure to enable the retraction of the transfer material as heretofore described which allows the strips if disarranged to automatically straighten out preparatory to the next writing operation. Such strips are at all times in registry as they reach the compensating roller or guide.

10 Although, in the ordinary operation of the apparatus the frictional feeding means associated with the platen roller 16 and the pin type feeding means associated with the compensating means, whether pinwheel units or the belt conveyors as illustrated are operated at equal speed to advance succeeding portions of the strips uniformly, for certain conditions of operation and for material of certain characteristics it is desirable to effect a slight differential of feeding action of the respective devices. This may be effected by making the pinwheel units of slightly different diameter than the platen roll 16 or by slightly changing the drive connection between the platen roll and the conveyor belt so that the conveyor belt is given a slightly different feeding ratio. Any differential of feeding ratio of the respective devices is compensated by the periodic release of the record strips from the frictional feeding means associated with the platen roll which relieves the strips of strain and permits their automatic readjustment.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect and the invention is therefore claimed in any of its forms or modifications within the legitimate and valid scope of the appended claims.

Having thus described our invention, we claim:

1. In a writing machine the combination of a positive feeding means for aligning and feeding a plurality of superposed strips of record material and a friction feeding means for feeding the record material, a platen roll associated with one of said feeding means around a portion of which the record material is fed circumferentially, and a guide intermediate said feeding means for causing the record material to follow a curvilinear path wherein the displacement of one sheet with respect to another caused by the curvature of the platen is compensated.
- 65 2. In a writing machine the combination of a positive feeding means for aligning and feeding a plurality of superposed strips of record material and a friction feeding means for feeding the record material, a platen roll associated with one of said feeding means around a portion of which the record material is fed circumferentially, and a guide intermediate said feeding means for causing the record material to follow a curvilinear path wherein the displacement of one sheet with respect to another caused by the curvature

of the platen is compensated, and means for releasing the friction feeding means at will to compensate and eliminate discrepancies of feed between the two feeds caused by the inaccuracy of the friction feed.

3. In a writing machine the combination of a positive feeding means for feeding a plurality of superposed strips of record material in registry, a friction feeding means for advancing the record material arranged in spaced relation with respect to the positive feeding means, a platen associated with one of said feeding means over at least a portion of which the record material travels through a curvilinear path, and means intermediate said feeding means for causing the record material to advance through another curvilinear path so as to compensate for the displacement of the sheets with respect to one another while passing over the platen.

4. The combination with a writing machine having a platen roller and associated frictional strip feeding means by which superposed record strips are collectively fed about the platen roll and past a writing position, of a pin type feeding device including progressively extensible and retractible pins operatively engageable with the strips in spaced relation with the platen roll, and about which the strips are fed through an arc of equal extent in converse relation to their passage about the platen roller, said pin type feeding means being so constructed and arranged that the record strips are misaligned during travel from said arc to the platen roller.

5. A manifolding apparatus for use with a writing machine having a platen roll and feeding means for advancing record material past writing position, including a main frame, a compensating roller mounted thereon in spaced relation with the platen roll of the writing machine and of substantially equal diameter, about which rolls continuous strips of record material are advanced in reverse relation whereby the outermost strip passing one roll is the innermost when passing the other roll, feeding pins carried by said compensating roll and operatively engaging with the strips, a transfer sheet carrier mounted upon the frame for reciprocatory motion intermediate the compensating roll and platen roll and an operative connection between the traveling transfer material carrier and the compensating roll.

6. The herein described method of advancing superposed strips of record material to a writing machine, including the steps of feeding the record material into registry along one path, feeding the strips in another parallel path offset thereto, advancing the strips intermediate said paths in such relation that as the strips are brought into registry in said first path, the strips simultaneously shift into registry in the other path.

7. In an apparatus of the character described, frictional means for advancing superposed record strips through an arcuate path toward a writing position, and guide means for directing the strips through an arcuate path of travel of equal angular extent and the converse of that before mentioned and feeding means positively engaging the strips throughout a portion only of the last mentioned converse arcuate path of travel for advancing the strips to said frictional feeding means, said feeding means being so constructed and arranged that the record strips are misaligned during travel from said guide means to the first mentioned arcuate path of travel.

8. In an apparatus for use with a writing ma-

chine having frictional feeding means for advancing superposed record strips toward writing position, a pin type feeding means operatively engageable with the strips for feeding the strips in their approach to the writing machine, said frictional feeding means and the pin type feeding means being arranged to simultaneously feed the record strips in converse directions through arcuate paths of equal angular extent, said pin type feeding means being engageable with the strips throughout an arc of less extent than that through which the record strips are advanced thereby the respective feeding means being so constructed and arranged that the record strips are misaligned during travel from one feeding means to the other.

9. In an auxiliary apparatus for a writing machine having a rotary platen and having strip feeding means associated therewith, for feeding superposed strips about said platen, a compensating roller in parallel spaced relation with the rotary platen about which the superposed strips are fed in converse relation to their direction of travel about the platen roll, and additional strip feeding means associated with the compensating roller having operative engagement with the strips for advancing the strips about the compensating roller through a path of equal angular extent in unison with their advancement about the rotary platen.

10. In a manifolding apparatus for use with a writing machine for inscribing multiple superposed plies of record material, means for supporting sheets of transfer material independently of and in alternating relation with the superposed plies of record material, including hanger bars projecting therebetween from which the transfer sheets are suspended, and a pivotal mounting for the hanger bars located at one side of the path of travel of the record material about which the hanger bars are swingingly adjustable.

11. In a manifolding apparatus for use with a writing machine for inscribing multiple superposed plies of record material, means for supporting sheets of transfer material independently of and in alternating relation with the superposed plies of record material, including hanger bars projecting therebetween from which the transfer sheets are suspended, a pivotally mounted support for the hanger bars and means for holding the support in any one of several different positions of oscillatory adjustment.

12. In a manifolding apparatus for use with a writing machine for inscribing multiple superposed plies of record material, means for supporting sheets of transfer material independently of and in alternating relation with the superposed plies of record material, including hanger bars projecting therebetween from which the

transfer sheets are suspended, said bars being angularly adjustable relative to the record material in planes parallel thereto.

13. In a manifolding apparatus for use with a writing machine having record material feeding means, a guide frame, a traveling transfer material carrier mounted thereon for to and fro reciprocatory motion, an operator slide also mounted on the frame for to and fro reciprocatory motion in a path of travel parallel to that of the transfer material carrier in a direction opposite to the movement thereof, and a flexible cable connecting the transfer material carrier and the operator slide by which motion is transmitted from the operator slide to the carrier.

14. An apparatus for use with a writing machine having a platen roll about which superposed record strips are advanced past a writing position, including a compensating roll in spaced relation with the platen roll and revoluble independently thereof about which the record strips are advanced to the platen roll in converse relation to their passage thereabout through arcuate paths of substantially equal extent, said compensating roll being actuated by the movement of the paper thereabout, and a series of radial pins carried by one of said rolls engageable in marginally punched holes in the record strips for assuring alignment and registry thereof as they pass the writing position.

15. An apparatus for use with a writing machine having a platen roll about which superposed record strips are advanced past a writing position, of an idler pin wheel device engageable in marginally punched holes in the record material in spaced relation with the platen roll and revoluble independently thereof about which the strips are advanced to the platen roll in converse relation to their passage about said platen roll through reverse arcuate paths of substantially equal extent for assuring alignment and registry of the strips as they pass the writing position.

16. An apparatus for use with a writing machine having a platen roll about which superposed record strips are advanced past a writing position, a guide means in spaced relation with the platen roll about which the record strips are advanced differentially with their advancement about the platen roll in converse order to their passage thereabout through reverse arcuate paths of substantially equal extent, and a travelling pin type device progressively engageable in longitudinally spaced holes in the record material during advancement thereof for assuring registry and alignment of the strips at the writing position.
